United States Patent Office

Des. 191,358
Patented Sept. 19, 1961

191,358

REMOTE CONTROL SWITCH UNIT OR SIMILAR ARTICLE

Allen R. Obergfell, Niles, Ill., assignor to Bell & Howell
Company, Chicago, Ill., a corporation of Illinois

Filed Oct. 24, 1960, Ser. No. 62,591

Term of patent 14 years

(Cl. D26—13)

FIG. 1.

FIG. 2.

FIGURE 1 is a perspective view of a remote control switch unit or similar article embodying my new design; and

FIGURE 2 is another perspective view of the same showing the sides thereof opposite those shown in FIGURE 1.

I claim:

The ornamental design for a remote control switch unit or similar article, as shown.
